United States Patent

Des. 242,108
Patented Nov. 2, 1976

242,108

COVER FOR A BEVERAGE CUP OR THE LIKE

William A. Dart, Mason, Mich., assignor to Dart
Container Corporation, Mason, Mich.

Filed Mar. 31, 1975, Ser. No. 563,564

Term of patent 14 years

Int. Cl. D7—01

U.S. Cl. D7—40

FIG. 1

FIG. 2

FIG. 3

FIG. 5

FIG. 4

—FIG. 6

—FIG. 7

—FIG. 9

—FIG. 8

FIG. 1 is a perspective view of a cover for a beverage cup or the like showing my new design.

FIG. 2 is a top view thereof.

FIG. 3 is a side elevational view thereof, the opposite side being a mirror image thereof.

FIG. 4 is a bottom view thereof.

FIG. 5 is a front elevation view thereof.

FIG. 6 is a sectional view thereof taken on line 6-6 of FIG. 2.

FIG. 7 is a sectional view thereof taken on line 7-7 of FIG. 2.

FIG. 8 is a partial sectional view thereof taken on line 8-8 of FIG. 3 and showing a modification thereof having vent members on the annular rim thereof.

FIG. 9 is a partial sectional view thereof on an enlarged scale taken on line 9-9 of FIG. 8.

I claim:

The ornamental design for a cover for a beverage cup or the like, as shown and described.
